UNITED STATES PATENT OFFICE.

EDWARD W. HARRAL, OF BRIDGEPORT, CONNECTICUT.

DESIGN FOR A GOLF-CLUB PROTECTOR.

SPECIFICATION forming part of Design No. 29,634, dated November 8, 1898.

Application filed October 17, 1898. Serial No. 693,836. Term of patent 8½ years.

To all whom it may concern:

Be it known that I, EDWARD W. HARRAL, a citizen of the United States, residing at Bridgeport, in the county of Fairfield and State of Connecticut, have invented and produced a new and original Design for a Golf-Club Protector; and I do hereby declare the following to be a full, clear, and exact description of the invention, such as will enable others skilled in the art to which it appertains to make and use the same.

Referring to the accompanying drawings, Figure 1 is a side elevation of my newly-designed golf-club protector; Fig. 2, an edge elevation looking at the edge at the right of Fig. 1, and Fig. 3 an edge elevation looking at the edge at the left of Fig. 1.

Similar numbers of reference denote like parts in the several figures of the drawings.

My design particularly relates to a cover resembling somewhat an ordinary sock for the foot, the cover being drawn over the head of the golf-club to protect the same from rain, snow, or other inclemency of the weather.

The essential features of my design are the plain shank-like portion and the enlarged knob-like portion surmounting and terminating said shank portion.

1 is the shank-like portion, and 2 the knob-like portion. 30

I claim—

The design for a golf-club protector as herein shown and described.

In testimony whereof I affix my signature in presence of two witnesses.

EDWARD W. HARRAL.
